UNITED STATES PATENT OFFICE.

NORMAN T. HARRINGTON, OF CLEVELAND, OHIO.

HOISTING MECHANISM.

Application filed November 14, 1921. Serial No. 515,089.

To all whom it may concern:

Be it known that I, NORMAN T. HARRINGTON, a citizen of the United States, residing at Cleveland, in the county of Cuyahoga and State of Ohio, have invented certain new and useful Improvements in Hoisting Mechanism, of which the following is a specification.

My invention relates generally to hoisting mechanism and more particularly to such mechanism used in connection with aerial cableways and load-handling devices of similar character.

As is well known load-handling devices of this type comprise means for raising and lowering and imparting lateral movement to the bucket; for instance the usual clam-shell bucket, and for opening and closing it.

The principle object of this invention is to provide means for positively and conveniently controlling the operation of the bucket.

Another more specific object is to provide means for conveniently controlling the closing and opening operation and the hoisting and lowering operation of the bucket at will during the travel of the carriage on the cable way.

Another object is an arrangement which is economical in operation.

In order to explain the characteristic features of the invention, the principles upon which it is based and the advantages derived from it, reference may be made to two well known standard systems of reeving in general application.

In the one system, usually referred to as the English system, the hoisting line is attached at one end adjacent one end of the cable way, then passes over a group of sheaves on the carriage and on the bucket to a drum adjacent the tower supporting the other end of the cableway. This system of reeving affords a good control of the bucket independently of the travelling movement of the carriage, but at the usually high speeds of the carriage the wear of the hoisting cable in passing over the commonly and necessarily small sheaves is excessive. Aside

from this point, the power necessary to overcome the friction between the hoisting cable and its sheaves in addition to the power necessary to haul the carriage with the bucket is considerable, amounting to 5-15 horsepower according to the speed of operation and other conditions as to the size of the sheaves, load, etc.

In the other system, commonly referred to as the American system of reeving, one end of the hoist line is attached to the carriage, then passes over a sheave or sheaves on the bucket and a sheave or sheaves on the carriage to the hoisting drum. In this case, if it is intended to keep the bucket at a certain height during the travel of the carriage, the hoist line will have to be taken up or paid out by the hoisting drum at the same rate as the carriage travels to one side or the other, as the case may be. The hoisting drum and the travel line drum are therefore usually operated at the same time during the travelling operation. If it is intended to hoist during the hauling or travelling operation, the operator resorts to the practice of letting the clutch of the travel line drum slip so that the hoist line is enabled to gain on the travel-line. Conversely, if the operator wants to lower the bucket while the carriage is travelling, he lets the clutch of the hoisting drum slip to cause the hoist line to be taken up at a slower rate or to be paid out at a greater rate, as the case may be. This expedient is not only detrimental, but above all requires a skilled operator to practice it and is therefore, at best, expensive.

On the other hand this practice has the advantage over the English system that the wear on the hoist line and the power necessary for hauling are kept relatively low.

The present invention aims to combine the advantages of both systems without incurring the disadvantages of either. The system of reeving adopted is essentially the American system. However, in addition means are provided to afford control of the movement of the bucket independently of the movement of the carriage and these

means constitute the subject matter of the invention.

Briefly stated, the invention comprises a hoist line according to the American system of reeving, means for operating at will the hoisting drum and the travel line drum at such speeds that the bucket or other load will remain at the same height during the travel of the carriage and means for varying, at will, the speed of the hoisting drum relatively to the speed of the travel line drum. The principal and characteristic feature of the invention is a differential motion element interposed between the two drums.

16 While reference has been made only to the hoist line, the arrangement includes the closing line for the bucket, a closing drum and substantially similar means for controlling the closing line, the hoist line and closing line being of course subject to the same laws of operation.

For a full understanding of the invention reference is had to the accompanying drawings in which—

25 Fig. 1 is an elevation of a cableway and hoisting mechanism embodying the invention;

Fig. 2 is a horizontal section through the hoisting mechanism;

30 Fig. 3 is a schematic view showing the main parts of the hoisting mechanism in elevation;

Fig. 4 is a horizontal section of a modified form of hoisting mechanism;

35 Fig. 5 is a plan view, partly in section of another form of mechanism embodying the invention; and

Fig. 6 is a schematic representation of a counterweighted hoist mechanism.

40 The arrangement in Fig. 1 which shows the general disposition and operative relation of the features constituting the invention is a load-handling device in which 1 and 2 represent towers pivotally supported at the bottom and interconnected by a cableway 3. The guys and tilting cables for supporting and rocking the towers, respectively, are not shown and form no part of this invention. The carriage 4 is supported on the cableway by means of the usual wheels 5 and may be operated in the usual way by means of a hauling rope or cable 6 connected at one end to the carriage, then passing over a sheave 7 on one tower to and over a sheave 8 on the second tower to the drum 9, about which it may be dead ended or wound several times to obtain the necessary amount of friction, and finally passing over another sheave 10 near sheave 8 to the other side of the carriage. The hoisting line 11 and the closing line 12 are both connected at one end to the carriage at the respective points of attachment 11^a and 12^a. From the point 11^a the hoist line 11 passes over a sheave 11^b on the bucket 20 and a sheave 11^c on the

carriage 4 to and over sheave 14 on tower 1 down to and over sheave 16, to the drum 18, on which it is wound.

Similarly the closing line 12 passes from the point of attachment 12^a over sheaves 12^b and 12^c on the bucket over a sheave on the carriage (behind the sheave 11^c), over sheaves 15 and 17 to drum 19 to which its free end is secured. The bucket 20 more or less diagrammatically indicated represents the usual clam-shell type the operation of which is well understood.

The system of reeving, as previously referred to, is in substance the American system.

80 The arrangement of the parts including the carriage, the bucket, closing line, the hoisting line and the travel line, is thus generally the same as met with in practice.

85 The invention is embodied in the hoisting mechanism shown in broad outlines at the bottom right hand of Fig. 1.

Having now reference to Figs. 2 and 3, which represent a form adapted for operation from a common power shaft driven by a steam engine or other single power plant, the arrangement includes as the main elements a frame 21 carrying the power shaft 22 to which are keyed two pinions 23 and 24. The pinion 23 is in mesh with a gear 25 keyed to a shaft 26 while pinion 24 is in mesh with a gear 27 loosely mounted on a shaft 28. The gear 27 may be positively connected with shaft 28 by means of a clutch mechanism 29. It is understood that any form of clutch mechanism may be applied and that the illustration is merely intended to outline generally the use of a clutch rather than a particular form. The shaft 28 carries a drum or rather a wheel 30 having an elliptical groove 31 for receiving the turns of the travel line 6 indicated in Fig. 1, a brake 31^a and a gear 32.

Upon the shaft 26 is mounted aside from the previously mentioned gear 25 a combined external and internal gear 33, the hoisting drum 34, an element 35 carrying a brake 36 and an external gear 37, and a clutch mechanism 38.

110 The gear 33^a is in mesh with the gear 32 and the gear 33^b in mesh with pinions 39. The combined gear 33 may be positively connected to shaft 26 by means of a clutch 40. The pinions 39 are mounted on the ends of shafts 41 which extend through the body 115 of the drum 34 and carry at their other ends pinions 42 in mesh with the gear 37 previously mentioned. The pinions 39, shafts 41 and pinions 42 may be called the driven member of the differential motion mechanism while the gears 33^b and 37 are the driving members.

120 The gear 25 is in mesh with a gear 43 positively connected with the shaft 44 carrying the closing line drum 45. The mech- 130

anism on shaft 44 is identical with that upon shaft 26 with the single exception that the combined external and internal gear 46 corresponding to gear 33 is without a clutch connection to shaft 44. The gear 46 is in mesh with gear 33. It is thus apparent that the gears 32, 33 and 46 form an interdependent gear train which is in motion or at rest as a unit.

10 The operation is as follows:

The power shaft 22 is necessarily always driven in the same direction. The clutches 29 and 40 are ordinarily disconnected. When it is intended to move the carriage in 15 one direction from a certain point on the cableway without affecting the condition of the bucket, one of the two clutches 29 or 40 is operated by means of the push pin 29^a or 40^a respectively. Assuming that the clutch 29 is set into operation, power is transmitted from pinion 24 to shaft 28 through gear 27 turning the wheel 30. At the same time motion is transmitted from shaft 28 through gear 32 to gears 33 and 46. Clutches 38 and 25 47 are normally out of engagement and the brakes 36 and 51 are normally applied. The elements 35 and 48 are thus normally stationary. The gear ratio of the gear 33^b, pinions 39, pinions 42 and gear 37 is such 30 that under the conditions assumed the drums 34 and 45 will have the same angular velocity as wheel 30. The lines wound on wheel 30 and drums 34 and 45 are of course so related that while the carriage travels 35 toward the hoisting mechanism the closing line and the hoisting line are wound up on the respective drums and that when the carriage travels in a direction away from the hoisting mechanism the drums are turned 40 in a direction to unreel the closing line and hoisting line.

It is of course not necessary that the drums 34 and 45 should move at the same angular velocity. The diameters of the 45 drums and of wheel 30 respectively and the gear ratios in question may be so designed that the travel line and the hoist and closing lines have the same rate of motion whether the wheel 30 has the same diameter as the 50 drums or a different diameter.

When it is intended to move the carriage in the opposite direction, clutch 40 must be operated in place of clutch 29. The clutches thus serve the purpose of determining the 55 direction of travel.

If it is intended to hoist before travelling, the clutches 29 and 40 are kept in inoperative position and the clutch 47 is actuated. The power is transmitted from pinion 23 60 through the gear 25 to the gear 43 and shaft 44. The element 48 is thus connected through the clutch 47 to the shaft 44 and revolves therewith and at the same time drives the pinions 49. It must be understood 65 that when the clutches 29 and 40 are inop-

erative, the brake 31^a is applied. The gear train 32, 33 and 46 is thus stationary. The action of the revolving element 48 on the pinions 49 will thus cause the pinions 50 to travel along the internal gear 46^b rotating 70 thereby the drum 45 in the direction necessary to wind up the closing line.

When the bucket is closed, the clutch 38 may be actuated whereby the drum 34 is revolved in the direction necessary to hoist the 75 bucket. Just as soon as the clutch 38 is set into operation both drums will revolve at the same speed taking in the hoist line and closing line at the same rate and the bucket will be hoisted.

When it is intended to lower the bucket, it is merely necessary to simultaneously partly release the brakes 36 and 51 allowing the weight of the bucket to overcome the 80 frictional resistance of the brakes, while the 85 clutches 38 and 47 are disconnected. When the desired position is reached for opening the bucket, the brake 51 may be entirely released and the usual weights on the bucket will open the shells while the brake 36 may 90 be again fully applied or so applied as to retard the drum 34 relatively to the drum 45.

When it is intended to travel and hoist at the same time, the clutch 47 is applied to 95 first close the bucket and then the clutch 38 is applied to hoist. Then either clutch 29 or 40 is applied to travel in the desired direction.

As previously explained, an incident of 100 the pure travelling operation is the motion of the two drums 34 and 45 and of the wheel 30 so that the hoist line, the closing line and the travel line move at the same rate. This rate of motion is attained while the elements 105 35 and 48 are stationary. Now when the clutches 38 and 47 are in action while the carriage travels toward the hoisting mechanism, the differential speed of the drums 34 and 45 will be greater than when the elements 110 35 and 48 were at rest so that the hoisting and closing lines are traveling at a greater rate than the traveling line thereby hoisting the bucket. According to whether the bucket reaches its desired height before 115 the carriage reaches the desired point on the cableway or vice versa the clutches 38 and 47 are disconnected before the clutch 40 or 29 is disconnected or vice versa.

When the clutches 38 and 47 are in action 120 while the carriage travels in the direction away from the hoisting mechanism, the differential speed of the drums 34 and 45 will be decreased and the hoist and closing lines will travel at a speed less than that of the 125 travel line, thereby causing a hoisting of the bucket.

To lower the bucket while the carriage is travelling it is merely necessary to partly release the brakes 36 and 51 while the 130

clutches 38 and 47 are inoperative. When the carriage travels toward the hoisting mechanism, the release of the brakes will allow the elements 35 and 48 to revolve thereby decreasing the differential speed of the drums 34 and 45 and causing the hoist and closing lines to travel at a lower rate than the travel line. When the carriage travels in the opposite direction the release of the brakes 36 and 51 will conversely cause an increase of the differential speed of the drums thereby causing the hoist and closing lines to move at a higher rate than the travel line.

15 It is thus clear that the different motions of the carriage, of the bucket and the opening and closing thereof may be readily and easily controlled by the simple operation of certain elements as by the movement of levers. Whether the carriage travels in one direction or the other simultaneous actuation of the clutches 47 and 38 and release of brakes 36 and 51 will effect the hoisting operation and application of the brakes 20 while the clutches 47 and 38 are disconnected will bring about the lowering operation, while the simultaneous actuation of the clutch 47 and release of brake 51 alone effects the closing of the bucket and the release of brake 51 alone when the clutch 47 is open effects the opening of the bucket.

The arrangement shown in Fig. 4 is in principle the same as that shown in Figs. 2 and 3. The electric motor 60 through shaft 35 61 and pinion 62 drives the gear train composed of the gears 63, 64 and 65 which in turn are connected to the shafts 66, 67 and 68. Shaft 66 carries the travel wheel 69 while the drums 70 and 71 are loosely mounted on shafts 67 and 68 respectively. Through the internal gear 72, pinions 74, shafts 75, pinions 76, and gear 77, which latter is normally stationary, the differential speed of the drum 70 is such that the hoist line wound on it travels at the same speed as the travel line upon wheel 69. When the motor 78 is set into operation, the gear 77 is rotated thereby increasing or decreasing the normal differential speed of the 45 drum according to direction of travel of the carriage which is determined by the direction of rotation of motor 60. The same rules of operation apply of course also to the drum 71 and its operating mechanism which is identical with that for drum 70.

50 The availability of three separately controlled motors 60, 78 and 79 leads of course to a considerable simplification in the arrangement as is obvious.

60 The operation, briefly stated, is as follows: Motor 60 is operated in one direction to cause the carriage to travel in one direction and reversed to cause it to travel in the opposite direction. The drums 70 and 71 65 will simultaneously rotate in the proper di-

rections, to wind up the lines or pay them out at the same rate at which the travel line travels according to the direction of travel of the carriage. In order to close the bucket and hoist, motor 79 is operated until the bucket is closed and then both motors, 78 and 79, are operated to hoist. In order to lower and open the bucket both motors, 78 and 79, are operated in the opposite direction to lower and then motor 79 is operated alone to open. To simultaneously travel and hoist or lower, the three motors are simultaneously operated in the proper directions. By operating motor 79 alone the bucket may be closed or opened while the bucket is otherwise at rest. By operating the motors 79 and 78 simultaneously while the motor 60 is inoperative, the bucket may be hoisted or lowered while the carriage is at rest.

65 The form of mechanism shown in Fig. 5 is generally similar to the forms previously described, the principal difference being another form of differential motion mechanism.

70 The gears 80, 81 and 82 being in mesh and keyed to the shafts 83, 84 and 85 respectively, these shafts are driven in unison by means of the motor 86 which carries a pinion (not shown) in mesh with the gears 81.

75 The motor 88 drives the shaft 89 through a pinion 90 and a gear 91. The shaft 89 carries a pinion 92 in mesh with a gear 93 on which is mounted a bevel gear 94 which together with the bevel pinions 95 and the bevel gear 96 forms the differential motion element.

80 The bevel gear 94 is loosely mounted on the shaft 84 and the bevel gear 96 is rigidly connected with the drum 102 and together with it likewise loosely mounted on the shaft 84, while the studs 98 which carry the pinions 94 are fixed upon the shaft 84.

85 The bevel gear 94 on the one hand and the spider including studs 98 and pinions 95 on the other hand may be called the driving members, while the gear 96 may be called the driven member of the differential gear mechanism.

90 The motor 99 is similarly connected to the drum 103 through a differential motion mechanism, which is identical with the differential motion mechanism just described.

95 In practice the motors are provided with automatic brakes.

100 The operation briefly stated is as follows: The motor 86 drives the gear train 80, 81 and 82 and thereby the shafts 83, 84 and 85. The wheel 101 is thus driven directly from shaft 83, while the drums 102 and 103 are indirectly driven through the differential motion elements described. When the motor 86 alone is in operation, the gears 93 and 100 are at rest. It is understood that suitable 105 brake mechanism may be provided for nor- 110

5 mally holding the gear mechanisms connected with each of the motors at rest. While there is considerable latitude in this respect, I prefer magnetic brakes mounted on the ends of the shafts of the motors 86, 88 and 99 and normally operating to impede rotary movement of these shafts.

10 While the gears 93 and 100 are at rest, the drums 102 and 103 are rotated at a definite speed by operation of motor 86. When either or both of the motors 88 and 99 are set into operation, the speed of the drums is varied, i. e. increased or decreased according to the 15 relative directions of motion of the motors 86, 88 and 99. The control of the different operations of closing or opening the bucket, hoisting or lowering the bucket and travelling is thus absolutely positive like in the arrangements previously described.

20 As pointed out in the introductory remarks, one of the objects of the invention is economy in operation. The advantages of a system such as described, in connection with the American system of reeving are obvious 25 to the expert.

To carry the idea leading to the economy due to this arrangement to a logical conclusion, I propose to counterweight the bucket and thereby reduce the power necessary for 30 the operation of the hoisting mechanism to a minimum.

It may be generally stated that a counterweight may be operatively connected with 35 all forms of hoisting mechanism embodying the invention. It is more particularly applicable, however, to mechanism in which separate motor means are employed for hoisting and lowering, such mechanism being exemplified in Figs. 4 and 5.

40 In the arrangement shown in Fig. 4 a counterweight could be readily applied by providing the part carrying the gear 77 with a wheel or drum and attaching a rope to it carrying the counterweight.

45 However, to more fully indicate the applicability of a counterweight, drums 105 and 106 are connected to and carried by the gears 93 and 100 in Fig. 5. It is understood that these or like drums must be connected to those parts of the differential motion elements, whatever their form may be, which move only when the bucket is hoisted or lowered. The application of drums 105 and 106 to the bevel gears 93 and 100 is therefore intended merely as generally suggestive 50 and is by no means limited to the particular association.

Fig. 6 shows a load handling system in 60 which the bucket is counterweighted. The hoisting mechanism 107 may be assumed to be generally similar to the forms shown in Figs. 4 and 5. A counterweight 108 is suspended from a sheave 109 in the bight of a cable 110 one end of which is attached to 65 a gear drum 105 on the motor side of the

differential motion element controlling the hoisting and lowering operation while the other end is attached to the corresponding part of the differential motion element controlling the closing and opening operation. 70

By this arrangement the action of the counterweight upon the drums is substantially equally divided between the two drums.

75 In the foregoing the structural embodiments are merely representative of the general class of means available for the purposes of the invention.

While I have particularly referred to load handling devices including a cableway and a double line bucket, the invention is by no means limited thereto, as is obvious to the expert. The invention is applicable in all types of load-handling devices in which with the American system of reeving there is the necessity that the hoist line and another line shall travel at the same speed except at the time of dumping or returning to the normal position. 80

85 I claim—

1. In hoisting mechanism, the combination of two drums disposed laterally of each other and means operable at will to rotate the drums at substantially the same speed or to selectively vary the speed of either one of the drums to increase or decrease its speed relatively to the other drum, said means including separate differential motion mechanism for each of the drums and separately controllable motor 95 means for actuating one of the driving members of each of the drums. 100

2. In hoisting mechanism, two drums, a differential driving mechanism having its driven member connected to one of the drums, a second differential motion mechanism having its driven member connected to the second drum, means for simultaneously driving one of the driving members of each differential mechanism and means for separately driving each of the other driving members of the differential mechanism. 105

3. In hoisting mechanism, the combination of two drums disposed laterally of each other, shafts loosely extending through said drums and means operable at will to rotate the drums at substantially the same speed or to selectively vary the speed of either one of the drums to increase or decrease its speed relatively to the other drum, said means including separate differential motion mechanisms having their driven members connected to the two drums respectively and motor means for controlling the driving members of the differential motion mechanisms. 115

4. In hoisting mechanism, three drums, a differential motion mechanism having its driven member connected to one of the drums, a second differential driving mecha- 120

nism, having its driven member connected to another drum, means for simultaneously driving the third drum and one of the driving members of each differential mechanism and means for separately driving each of the other driving members of the differential mechanism.

5. In hoisting mechanism, the combination of three drums, differential motion mechanism having its driven member connected to one of the drums, differential motion mechanism having its driven member connected to another drum, reversible motor means and transmission mechanism for simultaneously driving the third drum and one driving member of each differential motion mechanism and reversible motor means for separately driving the other driving member of each differential motion mechanism.

6. In hoisting mechanism, the combination of two lines, one being a hoist line, a drum for each line, differential motion mechanism having its driven member con-

nected to the hoist line drum, means for simultaneously driving the other drum and one driving member of the differential motion mechanism, means for separately driving the other driving member of the differential motion mechanism and a drum on said other driving member for receiving a rope carrying a counterweight.

7. In hoisting mechanism, the combination of a hoisting drum, differential motion mechanism having its driven members connected to the drum, means for separately controlling the driving elements of the differential motion mechanism, a rope carrying a weight, a drum for receiving the rope and means for connecting the drum with the driven member of the differential motion mechanism in driving relation to bring the action of the weight in opposition to the weight acting on the hoisting drum.

In testimony whereof, I affix my signature.

NORMAN T. HARRINGTON.
